UNITED STATES PATENT OFFICE.

CLARENCE B. HOWE, OF UTICA, NEW YORK.

GARMENT STEAMING AND PRESSING MACHINE.

1,080,695.

Specification of Letters Patent.

Patented Dec. 9, 1913.

Application filed June 3, 1910. Serial No. 564,761.

To all whom it may concern:

Be it known that I, CLARENCE B. HOWE, citizen of the United States, residing at Utica, in the county of Oneida and State of 5 New York, have invented certain new and useful Improvements in Garment Steaming and Pressing Machines, of which the following is a specification, reference being had therein to the accompanying drawing.

10 My invention relates to improvements in garment steaming and pressing machines and I declare the following to be a full, clear, concise and exact description thereof sufficient to enable any one skilled in the art to 15 which it appertains to make and use the same reference being had to the accompanying drawings in which like reference characters refer to like parts throughout.

The object of the invention is to provide 20 an efficient machine to be used by pressers, cleaners, dyers, clothing manufacturers, knit goods manufacturers and cloth spongers and finishers whereby the renovating, refreshing and pressing of garments may be accomplished in a sanitary economical manner.

Further the machine contemplates a certain arrangement of the steam pipes whereby the steam may be admitted to parts of the buck at a time or to the whole surface of the 30 buck as desired.

The machine further contemplates means whereby the steam admitted to the buck will be sufficiently heated so as to render it dry, as is known in the art. Furthermore, the 35 machine will not shine, gloss or scorch any kind of fabric that it acts upon. Other objects will appear by reference to the specification and drawings in which latter—

Figure 1 is a perspective view of my machine complete; Fig. 2 is a side elevation of the same, certain parts being broken away; Fig. 3 is a detail enlarged of a casing employed to hold the head in elevated position; Fig. 4 is a detail enlarged of a rod employed 40 in connection with casing shown in Fig. 3; Fig. 5 is a section of a buck embodied in the machine; Fig. 6 is a plan view of the cover of the buck shown in Fig. 5; Figs. 7, 8 and 9 are details in plan, enlarged on the same 45 scale as Figs. 5 and 6, showing the separator plates; Fig. 10 is a side elevation in section of a smaller buck employed for specific parts such as the shoulder of the garment; Fig. 11 is a plan view of the cover of the shoulder buck; Figs. 12, 13 and 14 are details of the 50 partitions employed on the shoulder buck

shown in Fig. 10; Fig. 15 is a detail of the pipes disposed along the bottom of the buck shown in Fig. 10; Fig. 16 is a plan detail of the base or bottom of the buck shown in Fig. 60 10, showing the grooves therein for the drainage of the condensed steam; Fig. 17 shows a plan view of the pipe arrangement in the buck shown in Fig. 5; Fig. 18 is a plan view of the buck shown in Fig. 5 and 65 shows, the top and partition plates being removed, the grooves cast in the base thereof for the condensed steam from the buck; Fig. 19 is a plan view of the presser head of the buck, showing the steam pipes disposed in 70 the grooves cast therein; Fig. 20 is a plan view of the casing that fits over and is secured to the presser head shown in Fig. 19; Fig. 21 is a fragmentary perspective view of the levers adapted to effect the influx and 75 efflux of steam to the pipes shown in diagram in Fig. 17; Fig. 22 is a detail enlarged of a yoke employed to elevate the head of the buck; Figs. 23 and 24 are details of paddles that are used for finishing the pressed 80 garments. Fig. 25 is a detail somewhat enlarged of a bracket employed to mount a steam pipe to a leg of the machine; Fig. 26, is a front elevation partly in section of the machine; Fig. 27 is a detail of the head taken 85 on the line 27—27 of Fig. 26; Fig. 28, is a fragmentary view in detail, showing more particularly the cone shaped apertures in section; Fig. 29 is a fragmentary detail enlarged of a cone shaped aperture on one of 90 the separator plates; Fig. 30 is a detail view, showing a side elevation of a yoke employed; Fig. 31 is a detail enlarged, showing a lever, and its bearing in section, employed to actuate a cord for releasing the head; Fig. 32 is a 95 detail view, enlarged, showing a central vertical section of the casing shown in Fig. 3 and of parts in elevation related thereto, for releasing the head from its position upon the buck; Fig. 33 is a fragmentary view of 100 the head, showing the steam pipes connected thereto; Fig. 34 is a detail view enlarged, showing a vertical section of a spring valve employed to admit steam to the buck; Fig. 35 is a detail perspective view, showing fragmentary parts of the head; Fig. 36 is a detail enlarged, showing an elevation of a valve 105 employed to permit steam to escape from the pipes located in the head; Fig. 37 is a detail enlarged fragmentary view of a spring valve and pipes leading thereto and therefrom to admit steam to the shoulder buck; Fig. 38

is a detail enlarged perspective view of a bracket employed to provide a stop for the rotation of a yoke adapted to elevate the head; Fig. 39 is a cross-sectional view of the buck taken on line 39-39 of Fig. 18.

Referring more particularly to the drawings, I represent a table by 1 upon which is mounted buck 2 by a goose neck 3 adapted to hold the upper surface of buck 2 perfectly level. Buck 2 is preferably cast with grooves 4 in its base for the reception of steam pipes which I shall presently describe and may be also cast with integral sides and ends —a— and —b—, the end —a— being longer than end —b— in order that the upper surface of buck 2 shall be level and that the base —c— shall incline toward a drain pipe 15, when said buck 2 is disposed upon goose neck 3. The sides 5 are narrower at end —b— than at end —a— and the upper surfaces of the sides and ends are in the same horizontal plane. Ends —a— and —b— of the buck are provided with shoulders 6 upon which rest, when the parts are assembled, separator plates 8, 9 and 10 provided with cone shaped apertures as 11, 12 and 13 respectively. Apertures 11, 12 and 13 may be made by the process of punching and are so formed that holes 11 of the bottom plate 8 are the largest and those of the remaining plates diminish successively in size. Holes 11, 12 and 13 of plates 8, 9 and 10 are also so disposed as not to align with each other. Cover 14 is also provided with cone shaped apertures N, preferably smaller than any of those in plates 8, 9 and 10 and is secured to buck 2 by bolts e having heads I countersunk in cover 14 and nuts M countersunk in the base of buck 2 as shown in Fig. 5. Plates 8, 9 and 10 are supported centrally in assembled position by partition f soldered thereto. Plates 8, 9 and 10 and cover 14 are all easily removable from buck 2 for the purpose of cleaning of same when desired.

As before stated the sides 5 are wider at end *a* than at end *b* and by referring to Fig. 5 it will be noticed that plates 8, 9 and 10 are disposed within buck 2 in zigzag formation which arrangement together with the grooves 4 in base of the buck is adapted to permit the condensed steam to gravitate toward outlet pipe 15 provided with trap *d* and cock 16.

In Fig. 17 I have shown a diagrammatic plan view of the steam pipes as they are arranged in the buck. The steam enters by way of pipe 18 and proceeds along pipe 19 to pipes 19^a, 20 and 21. Pipe 19 is perforated along its opposite sides for about one half its length by small holes adapted to permit the escape of the steam and pipes 19^a, 20 and 21 are likewise perforated as here shown, for the escape of the steam.

This is to permit the steam to enter one-half of the buck only. In the event that it is desirous to allow the steam to enter the opposite half of the buck 2, I provide pipe 22 to admit the steam and pipes 23, 24 and 25 perforated along their opposite sides to distribute same.

Head 26 is preferably cast with grooves 110 for the suitable housing of pipes 27 arranged preferably as here shown in Fig. 19 and the same are covered with a sheet of asbestos paper 111 to prevent the escape of heat in the upward direction. Upon head 26 is mounted cover 27^a held rigidly thereto by screws 28. The steam enters pipes 27 through pipe 29 and may be allowed to escape through cock 30.

The mechanism for actuating the head 26 contemplates a yoke A provided with curved arms 36-36 secured to cover 27^a by bolts 37 and fulcrumed upon an axle 38 having bearings in the extended portions of rear legs 39-39. The yoke A is bifurcated as at 40 adapted to form a bearing for pivotally mounting rod 41 provided with a recess 42. Rod 41 is slidably mounted in casing 43 pivotally held to treadle 44 by bearings 45 integral with said casing 43 having near its upper portion a bracket 46 adapted to pivotally mount bell crank lever 47 whose arm 48 extends or projects through a recess in plunger pin 49 slidably mounted in sleeve 50 integral with casing 43 and having a central chamber connecting or opening into chamber 51 of casing 43, so that plunger pin 49 will project into chamber 51 and arrest the movement of rod 41 by engaging with recess 42 thereof. Plunger pin 49 is held normally inward against rod 41 by spring 51^a secured to elevation 52 of bracket 46 and to bell crank lever 47, as shown.

In order to offset or draw out plunger pin 49 from recess 42 of rod 41 I employ a cord 53 attached to the upper arm of bell crank lever 47 as at 54 and to an end of a second bell crank lever 55 pivotally mounted in a bearing 56 secured to yoke A shown in Fig. 22. Bell crank lever 55 is preferably located a little to the rear and above the bell crank lever 47. Another cord 57 is secured to the other arm of lever 55 and to a lever handle 58 pivotally mounted in a suitable bearing secured to cover 27^a as shown in Fig. 20. Obviously by pulling forward on lever handle 58 it will by means of the string connection just explained draw plunger pin 49 out from its engagement with notch 42 of rod 41 and permit said rod 41 pivoted to the rear of yoke A actuated by spring 60 to slide downward in casing 43 and thus allow spring 60 to rotate yoke A on its axis 38 and raise head 26 into the position shown in Fig. 2. A bracket 61 secured to the edge of the up-

- per surface of top of table 1 is a means against which yoke A abuts to provide a positive stop for the rotation of yoke A and the consequent raising of head 26.
- 5 The arrangement of the pipes for the influx of the steam to the head and the buck embodies a main pipe 62 provided with a cock 63. The steam may be supplied by means of a boiler 64 heated in any desirable manner. The steam moves from pipe 62 into pipe 69 and part of it moves into pipe 65 having a cock 66 adapted to regulate the movement of the steam into pipes 67 and 68 the latter being connected to pipe 67 by a swivel joint as 67a. The steam moves on into pipe 29 and pipes 27 in head 26 and may be allowed to escape by cock 30. The arrangement of the pipes as shown in Fig. 19 causes the condensed steam, when 10 the head 26 is raised, to gravitate toward pipe 29 and thence backward through pipes 68, 67, 65 and down pipe 69 where it collects in cylinder 70 and may be let out by cock 71. That part of the steam that does 15 not go through pipe 65 moves downward through pipe 69 into pipe 72 and part of this remainder moves up pipe 73 provided with a spring valve *k* of any ordinary construction, well known in the art, and said spring 20 valve *k* is actuated by a knee plunger 75 slidably mounted in bracket 76 pendant from the top of table 1. From pipe 73 the steam moves when permitted by the spring valve *k*, into pipes 23, 24 and 25 located in 25 buck 2. The yet remaining portion of the steam moves from pipe 73 to pipes 77 and 78 provided with a spring valve *l* similar to the valve *k* and is actuated by a knee plunger 81 similarly mounted to plunger 75 30 in the remote side of bracket 76. When valve *l* is opened the steam moves onward through pipes 79 and 80 to pipes 19, 19a, 20 and 21 also located in buck 2. In the event that the operator desires to permit the influx of steam to all the pipes in the buck 2 he pushes with his knee inward on plunger 82 having extended sides 83—83 on its head 35 adapted to abut against the corresponding adjacent shoulders 84—84 of the heads of plungers 75 and 81.
- To operate the machine the garment is placed upon the upper surface of buck 2, which surface is covered preferably with a layer of felt 112 covered with a layer of 40 woolen or linen cloth 113. The operator then manipulates handle 86 and brings head 26 down in to the position shown in Fig. 1 in which position plunger 49 engages recess 42 of rod 41 and thus holds the head 26 in the position here indicated. Cocks 63 and 66 are opened and the steam allowed to enter the head. The under or contact surface of the head 26 is likewise covered with felt and linen or woolen cloth 114 45 and is brought to bear on the garment on the buck by pressing down with the foot on treadle 44 fulcrumed in bracket bearing 88 pendant from cross rod 89 and pivotally mounted to casing 43 held stationary to rod 41 by plunger pin 49 engaging recess 42 50 thereof. Treadle 44 is further held in convenient central position by guide bracket 90 secured to cross bar 91 of table 1. The forcing down of lever 44 will by the connections just explained force rod 41 upward and the arms 36—36 of yoke A downward and consequently head 26 will come to bear upon the garment with any desired degree of pressure determined by the weight of the foot upon lever 44. Steam may now be let 55 into all the pipes in the buck, simultaneously, by pressing inward on central knee plunger 82 or the steam may be let into either end independently by pressing inward on either plunger 75 or 81 as desired. The releasing of the knee plungers 75, 81, or 82 causes the valves to close so that the steam can not enter, as is obvious. When the garment has been pressed sufficiently, the head will be automatically raised by 60 simply pulling forward on lever handle 58 which will, by the string connections heretofore explained, draw plunger pin 49 out from its engaging position in recess 42 of rod 41 and thus cause spring 60 to elevate 65 head 26 to the position shown in Fig. 2.
- In Fig. 25 I show a bracket 95 having an internally screw threaded sleeve 97 for the screw mounting of one end of pipe 67 to rear leg 39.
- In order to give a finishing effect to the garment the operator may apply thereto, by rubbing over the surface of the garment after the head 26 has been elevated a paddle such as 91 shown in Fig. 23 or as 92 shown 70 in Fig. 24, and may admit the steam to that part of the buck 2 over which the immediate part of the garment being worked upon is located, without the operator experiencing the discomfort of the excessive steam rising over the part on which he is not working.
- At 100 I show a small buck used to press more particularly the shoulders of garments, which can not be done so effectively upon buck 2. The small buck 100 is provided with a top 101 adapted to conform to the cut of the shoulder of a garment. Otherwise the buck 100 is constructed like buck 2 only on a much smaller scale. Steam is 75 allowed to enter by pipe 102 connected to pipe 73 and having a spring valve 103 actuated by a treadle 104. The condensed steam gravitates toward outlet pipe 105 whereby it may be drawn off.
- In the event that it is found desirable to have the steam for pressing the garment excessively dry, the plates 8, 9 and 10 of buck 2 may be turned over so as to rest on the opposite side from that shown in Fig. 5.

125

130

Having thus described my invention what I claim as new and desire to secure by Letters Patent is:

1. In a garment pressing and steaming machine, a buck provided with detachable partitions having apertures, and said partitions arranged in inclined zig zag formation adapted to render the steam passing through said buck dry. 5
2. In a garment steaming and pressing machine, a buck having steam pipes along its base, and partition members arranged in inclined zig zag formation, said partition members being provided with apertures adapted to render the steam passing therethrough dry. 10
3. In a machine of the character described, a buck provided with steam pipes and partition members disposed in inclined zig zag formation, cone shaped apertures in said partition members, said apertures adapted to render the steam passing therethrough dry. 15
4. In a garment steaming and pressing machine of the character described, a buck having steam pipes therein, means for admitting steam to said buck, means for automatically shutting off said steam from said buck, partition members disposed in inclined zig zag formation in said buck, and said partition members having apertures adapted to render the steam passing therethrough, dry, substantially as described. 20
5. In a garment steaming and pressing machine, a buck having steam pipes disposed along its base said base being inclined for the drainage of the condensed steam, means for opening and closing the valves to said pipes, and partition members disposed in inclined zig zag formation in said buck and having cone shaped apertures adapted to render the steam passing therethrough, dry, substantially as described. 25
6. In a machine of the character described, the combination of a buck and a head, said buck provided with steam pipes and partition members disposed in inclined zig zag formation, said partition members having cone shaped apertures adapted to render the steam passing therethrough, dry, lever means for bringing said head to bear on said buck, and automatic means for elevating said head from off said buck. 30
7. In a machine of the character described, the combination of a buck having steam pipes disposed along its base, said pipes being arranged to admit steam to either end of said buck, or to both ends thereof simultaneously, said pipes being perforated for the escape of the steam to the interior of said buck, partition members disposed in inclined zig zag formation in said buck, said partition members having cone shaped apertures adapted to render the steam passing therethrough, dry. 35
8. In a garment steaming and pressing machine, the combination of a buck having sides and ends cast integral therewith, said sides being narrower at one end than at the other, whereby the base of said buck may be held in inclined position by a goose neck, steam pipes arranged in grooves cast in said base of said buck, a drainage pipe for drawing off the condensed steam, partition members in said buck, said members having cone shaped apertures for the passage of steam from said steam pipes, means for holding said partitions in inclined zig zag formation, whereby the condensed steam will gravitate toward said drainage pipe, and a head adapted to bear on said buck for pressing and steaming garments. 40
9. In a garment steaming and pressing machine of the character described, the combination of a buck, a head, spring actuated valves for admitting steam to said buck, said buck being provided with partitions having cone shaped apertures for the passage of steam therethrough, said head having steam pipes arranged therein, so that the condensed steam will gravitate toward a drainage pipe, and automatic means for elevating said head. 45
10. In a garment steaming and pressing machine of the character described, the combination of a buck having partitions disposed in zig zag formation therein, said partitions having apertures adapted to render the steam passing therethrough dry, pipes in said buck, whereby steam may be admitted to either end thereof, valves opened by knee plungers to admit steam to said pipes, automatic means for closing said valves, a head having steam pipes therein, and lever means for bringing said head to bear on said buck. 50
11. In a garment steaming and pressing machine, the combination of a buck provided with partitions disposed on an incline to each other and having cone shaped apertures for the passage of steam, pipes arranged in said buck, spring valves actuated by knee plungers for admitting steam to either end of said buck, or to both ends thereof simultaneously, and a head having steam pipes arranged therein in a manner adapted to allow the condensed steam to gravitate toward a drainage pipe, when said head is in elevated position. 55
12. In a garment steaming and pressing machine, the combination of a buck, a head, steam pipes and spring valves, said buck being provided with partitions having cone shaped apertures for the passage of steam, means for holding said partitions in inclined zig zag formation, said pipes being disposed in said buck in a manner adapted to admit steam to either end of the buck, independently of the other, or to both ends si- 60

multaneously, and said valves adapted to admit steam to said pipes.

13. In a garment steaming and pressing machine, the combination of a buck having 5 steam separator plates disposed in a longitudinally inclined zig zag formation therein, said plates having cone shaped apertures for the passage of steam in small quantities, a head adapted to be brought to bear on said 10 buck, means for elevating said head, steam pipes arranged in said buck, whereby steam may be admitted to either end thereof, independently of each other, and steam pipes arranged in zig zag formation in said head.
14. In a garment steaming and pressing machine of the character described, the combination of a buck, steam pipes, and means 15 for supplying steam to said pipes, said buck being provided with detachable plates having cone shaped apertures for the passage of steam, pipes arranged in said buck, whereby steam may be distributed to either end, or to both ends simultaneously, of said buck, spring valves actuated by plungers and 20 adapted to open said pipes for the passage of steam, a head adapted to be brought to bear on said buck, and automatic means for elevating said head, substantially as described.
15. In a garment steaming and pressing machine, the combination of a buck, a head, steam pipes, and spring valves, said buck having separator plates disposed in zig zag formation in said buck and having a cover 25 with cone shaped apertures covered with cloth, plungers adapted to admit steam to either end, or to both ends simultaneously, of said buck, said head having therein steam pipes covered with a heat retaining sub-

stance, means for elevating said head, and 40 means for bringing said head to bear on said buck, whereby to press a garment.

16. In a garment steaming and pressing machine, a buck, cone shaped apertures in said buck, whereby to render the steam passing therethrough dry, spring valves for admitting steam to said buck, plungers for opening said valves, and a plunger for actuating the aforesaid plungers, whereby to open all of said valves simultaneously. 50

17. In a garment steaming and pressing machine, a buck having disposed therein partitions arranged on an incline and in zig zag formation, cone shaped apertures in 55 said partitions, and spring valves actuated by plungers, whereby to admit steam to said buck.

18. In a garment steaming and pressing machine, a buck having disposed therein partitions with apertures, and said partitions being detachably mounted in inclined position by shoulders, substantially as described. 60

19. In a garment steaming and pressing machine, the combination of a buck, a plurality of detachable partition members disposed therein on an incline to each other for the drainage of the condensed steam, cone shaped apertures in said partitions for the 65 passage of steam, and spring valves for the admission of steam to said buck. 70

In testimony whereof I have hereunto affixed my signature in the presence of two witnesses.

CLARENCE B. HOWE.
